DESIGN FOR AN AIRPLANE

Ruth Jones Brown, Middle River, Md., assignor to
The Glenn L. Martin Company, Baltimore,
Md.

Application August 12, 1943, Serial No. 110,902

Term of patent 7 years

(Cl. D71—1)

To all whom it may concern:

Be it known that I, Ruth Jones Brown, a citizen of the United States and a resident of Middle River, county of Baltimore, State of Maryland, have invented a new, original, and ornamental Design for an Airplane, of which the following is a specification, reference being had to the accompanying drawing, forming part thereof.

Figure 1 is a front elevational view of the subject airplane.

Figure 2 is a plan view of the airplane shown in Figure 1.

Figure 3 is a side elevational view of same.

I claim:

The ornamental design for an airplane, substantially as shown.

RUTH JONES BROWN.
